UNITED STATES PATENT OFFICE.

CHARLES MARTIN BAGSHAW, OF LEICESTER, ENGLAND, ASSIGNOR TO THE GIMSON SHOE MACHINERY COMPANY LIMITED, OF LEICESTER, ENGLAND, A CORPORATION OF GREAT BRITAIN.

PULLING-OVER AND LIKE MACHINE.

1,347,929.

Specification of Letters Patent. Patented July 27, 1920.

Application filed November 1, 1919. Serial No. 335,010.

To all whom it may concern:

Be it known that I, CHARLES MARTIN BAGSHAW, a subject of the King of Great Britain, residing at Leicester, in the county of 5 Leicester, England, have invented an Improvement in or Relating to Pulling-Over and like Machines, of which the following is a specification.

This invention relates to pulling-over and 10 like machines and concerns those of the type wherein two pincer devices are provided for each side of the shoe, each pair of devices being mounted in a single carrier or housing. In such machines there is usually employed 15 a single pincer mechanism for gripping the upper at the toe extremity while on each side of the toe the upper is gripped by the twin pincer mechanism aforesaid.

Obviously in shoes of different sizes and 20 shapes, the contour of the edge of the upper to be gripped by the twin pincers on either side of the toe will vary, this contour being determined more or less by the shape of the last. To enable the twin pincer mechanism 25 to be set so that the gripping jaws of each of its pincer devices occupy a position suitable for engaging the edge of the upper, the carrier or housing in which the pair of pincer devices is mounted has been arranged 30 for rotary adjustment, which adjustment has moved the two devices relatively to the last without however, altering the position of one device relatively to the other in the carrier or housing.

In order that the twin pincers may have 35 a better opportunity of engaging and imparting a square pulling strain upon the upper, it is desirable that provision should be made whereby the angular relationship between 40 the gripping faces of the pincer devices of each pair may be varied so that the grippers can conform more nearly to the contour of that part of the edge of the upper which they are to take hold of and pull. It 45 is also desirable that the pulling strain imparted by each twin pincer mechanism should be equally or approximately equally distributed between the individual devices composing said mechanism.

It is the object of the present invention to 50 provide for a pulling-over or like machine of the type previously referred to, an improved form of twin pincer mechanism embodying the above mentioned desirable features.

The invention therefore consists of a pincer mechanism of the kind wherein two pincer devices are mounted in a common carrier or housing the distinguishing feature being that said devices are capable of individual rotary adjustment within said carrier or housing for the purpose of varying the angular relationship of the faces of the gripping jaws of said devices, and that for imparting the pulling strain the said pincer 60 devices are operated from a common actuating member through the medium of a balancing or equalizing member.

In carrying the invention into effect, each pincer device of the pair is formed with a 70 round shank or case which fits both rotatably and slidably in a hole in the carrier or housing. The said case is supported in its hole by a spring and the actuating rods of the two devices are connected to a cross bar 75 to the center of which is connected an actuating member by which the cross bar is pulled down.

To enable the invention to be clearly understood a convenient form of the same is 80 shown in the accompanying drawing by way of example.

In the drawing:—

Figure 1 is a front elevation of a twin pincer arrangement according to this invention.

Fig. 2 is a side elevation of the same.

Fig. 3 is a plan of the associated pincer mechanism.

Throughout the drawings like parts are 90 designated by the same reference characters.

Referring to Figs. 1 and 2 the twin pincer mechanism comprises a carrier or housing 1 in which are mounted pincer cases 2 these being round in cross section and fitting both 95 rotatably and slidably in holes 3 in the carrier; each case 2 being supported in its hole by a compression spring 4 which surrounds a reduced or shank part 5 of the case. The pincer cases are furnished at the upper end 100 with a pair of pivoted gripping jaws 6, 7 combined with which is an inner rod 8 adapted upon downward movement to effect closure of the jaws. The gripping jaws and their actuating means are preferably of the 105 kind used in the prior mechanism described in United States Letters Patent No. 1293162.

The inner rod of each pincer device of the pair terminates in a ball 9 and connecting the balls of the two rods so as to be movable upon 110

each, is a cross bar 10 to the center of which is connected, preferably by a ball 11, a rod 12 or other convenient form of actuating member by which the cross bar is pulled down so that in turn it pulls upon the inner rods 8 of the two pincer devices. The cross bar is made in halves fastened together by screws the meeting faces of the two parts being cupped to form sockets for the purpose of engaging the balls 9 and 11.

The carrier or housing 1 is rotatably adjustable in its support 14 so that the two pincer devices can be positioned bodily to suit the curvature of the upper in addition to which each pincer device, being rotatable in the carrier 1, can be turned to such a position relatively to its companion device as will bring the faces of its gripper jaws to an approximate horizontal angle to engage the edge of the upper squarely, or in other words the gripper jaws 6, 7 can, by turning the pincer devices, be set or automatically set themselves so that their gripping faces are disposed substantially in line with the particular part of the edge of the upper they are to engage. This will be best understood by reference to Fig. 3 where in addition to the pincer mechanisms and gripping jaws already referred to, the opposite pincer cases 2^a and their grippers 6^a, 7^a are shown in association with the toe pincer mechanism 15.

Upon downward movement of the actuating member 12 to impart the initial strain, the inner rods 8 of the pincer devices close the gripping jaws upon the upper after which the pincer cases 2 move down in the carrier 1 against the pressure of their supporting springs 4. During this action the cross bar 10 accommodates itself to the resistance of the two pincer devices and allows, when necessary, greater movement of one than of the other so that the pulling strain upon the two parts of the upper engaged is equalized.

The ball connection 9 between the inner rods 8 of the pincer devices and the ball connections 11 between the cross bar 10 and the actuating member 12, enables the rotary adjustment of the carrier to take place without disturbing the operative connection of the parts. The rotation of the pincer cases in the carrier may be limited by suitable means such as a pin or key working within a groove. The rotary adjustment of the carrier or housing may be suitably restricted.

The carrier or housing 1 also carries the track driving, wipers and other associated parts comprising the pincer mechanism. With regard to the rotation of the pincer cases 2, 2^a in the carrier 1, this adjustment may be effected by hand or the said devices

may be freely turnable so that the jaws are positioned automatically during the stretching operation. Means may be provided for fixing the pincer devices against further rotation after they have been positioned.

What I claim then is:—

1. For a pulling-over machine, a pincer mechanism comprising two pincer devices, a carrier common to said devices, and capable of rotary adjustment, said devices being capable of individual rotary adjustment within said carrier for the purpose of varying the angular relationship of the gripping jaws of said devices, an actuating member common to the two pincer devices, and a balancing member through which the pulling strain is transmitted from the actuating member to the two pincer devices.

2. For a pulling-over machine, a pincer mechanism comprising two pincer devices, a carrier common to said devices and capable of rotary adjustment, said devices being capable of individual rotary adjustment within said carrier for the purpose of varying the angular relationship of the gripping jaws of said devices, a gripper closing rod in each pincer device, a cross bar pivotally connected to each gripper closing rod, and an actuating member pivotally connected to the cross bar at a point intermediate of the connections to the gripper closing rods.

3. For a pulling-over machine, a pincer mechanism comprising two pincer devices, a carrier common to said devices and capable of rotary adjustment, said devices being each formed with a round case which fits both rotatably and slidably in a hole in the carrier, a compression spring supporting each pincer device in the carrier, a gripper closing rod in each pincer device, a cross bar pivotally connected to each gripper closing rod, and an actuating member pivotally connected to the cross bar at a point intermediate of the connections to the gripper closing rods.

4. For a pulling-over machine, a pincer mechanism comprising, in combination, a carrier capable of rotary adjustment, two pincer devices each independently mounted rotatably and slidably in a hole in the said carrier, a compression spring supporting each pincer device, gripping jaws in each pincer device, a rod in each pincer device for closing said jaws, a cross bar, a ball and socket connection between each rod and the cross bar, an actuating member, and a ball and socket connection between the said member and the center of the cross bar.

In testimony whereof, I have signed my name to this specification.

CHARLES MARTIN BAGSHAW.
